COMBINED PIZZA PIE CUTTER AND SERVER

Harold G. Edgar, Pittsfield, N. H., assignor to Tucker Products Company, a corporation of Massachusetts

Application June 20, 1958, Serial No. 51,452

Term of patent 14 years

(Cl. D44—29)

Figure 1 is a perspective view of a combined pizza pie cutter and server showing my new design;

I claim:

The ornamental design for a combined pizza pie cutter and server, as shown.
